UNITED STATES PATENT OFFICE.

ROBERT E. MARTIN, OF SHERIDAN, WYOMING, ASSIGNOR OF THREE ONE-HUNDREDTHS TO LOUIS L. LIVINGSTON AND ONE-TWENTIETH TO EDWARD G. LIVINGSTON, BOTH OF SHERIDAN COUNTY, WYOMING.

SPARK ARRESTER.

Application filed March 8, 1926. Serial No. 93,299.

My present invention has to do with locomotive equipments designed to arrest sparks; and its general object is the provision of means in a locomotive adapted to effectively prevent the emission of spark from the locomotive smoke stack, and this without the employment of any reticulated or foraminous elements which are objectionable because of their liability to wear out after a short period of use.

Other objects and practical advantages of the invention will be fully understood from the following description and claims when the same are read in connection with the drawings, accompanying and forming part of this specification, in which:—

Figure 1 is a longitudinal vertical central section of so much of the forward portion of a locomotive as is necessary to illustrate the preferred embodiment of my invention.

Figure 2 is a transverse section, partly in elevation, the sectional portion being taken in the plane indicated by the line 2—2 of Figure 1.

Figure 3 is an enlarged detail perspective of one of the forward baffle members comprised in my improvement.

Similar numerals of reference designate corresponding parts in all of the views of the drawings.

In the preferred embodiment of my invention a chamber 1 is provided intermediate of a smoke stack 2 and the usual conduit 3 designed to receive exhaust steam from the piston cylinders of the locomotive.

The rear wall of the chamber 1 is formed by a baffle plate 4 below which is an opening 5 in communication with the chamber 1; and it will also be noticed in Figure 1 that the baffle plate 4 is spaced in front of the forward ends of the usual longitudinal flues 6 of the locomotive. Separated by an intervening space 7 from the baffle plate 4 and arranged in a vertical series are baffle members 8, preferably of concavo-convex form in vertical section, there being, by preference, four of the said baffle members 8, and the said members being separated from each other by intervening spaces and being ex-

tended throughout the width of the locomotive casing as will be understood from Figure 2. Below the series of baffle members 8 is disposed a chute 9, the lower end of which is adjacent to a transverse trough 10 in

which is a screw conveyor 11, the said trough 10 being equipped at one end and exterior of the locomotive casing with a spout 12, Figure 2, for the discharge of cinders and ashes received in the trough 10. Below the space immediately in rear of the series of baffle members 8 and adjacent to the chute plate 9 is a draft door 13 which is preferably employed, though it is not of my invention. The bottom of the chamber 1 is defined by a wall 14 through which the conduit 3 extends, and joined to the forward portion of the wall 14 is a curvilinear wall 15 which defines a portion of an arcuate conduit 16, the upper end of which is in communication with the forward portion of the chamber 1, and the lower end of which is in communication with the space below the wall 14. The forward wall of the arcuate or curvilinear conduit 16 is defined by a series of generally curved baffle members 17 and 18, the said members 17 and 18 being, by preference, relatively arranged as shown in Figure 1 and extending throughout the width of the boiler or locomotive casing, and the members 18 being of hollow character and tapered form as appears in Figures 1 and 3, the said form and character of the baffle members being advantageous inasmuch as the stiffness and strength of the same in proportion to their weight is increased.

Below the series of baffle members 17 and 18 is a transverse trough 19 with a discharge spout 20 at its end, Figure 2, and at this point I would have it understood that the said trough 19 is in communication with a vacuum chamber 21 disposed in front of the baffle members 17. In the trough 19 is a screw conveyor 22; and at this point I would have it understood that when occasion demands the screw conveyors 11 and 22 may be turned about their axes through any means that is deemed expedient, without affecting my invention.

My improvement is designed especially to arrest sparks without clogging or seriously diminishing the draft necessary in a locomotive; and by particular reference to Figure 1 it will be understood that my improvement is based upon the principle of centrifugal force in order to catch the heavy inflammable ashes and cinders ordinarily ejected through the uptake 2 of a locomotive by the

2
force of the exhaust discharged from the conduit 3. This will be better understood when it is stated that in the practical use of my improvement the draft maintained by the exhaust emitted from the conduit 3 draws heated gases, cinders, ash and inflammable particles and other products of combustion with tremendous force against the baffle members 8. The major portion of the burning ashes, cinders, etc., passes through the passageways between the plates 8 and is deflected downwardly into the trough 10 to be conveyed to a point exterior to the locomotive casing. A vacuum is maintained between the baffle members 8, on the one hand, and the baffle plate 4, on the other, and this vacuum is necessarily provided in locomotives at the point indicated in order to afford ample draft. Approximately three-fifths of the draft in the locomotive boiler is thrown against the baffle members 8 before passing down through the opening for draft controlled by the before mentioned door 13. The draft as a whole, is, however, forced through the stack 2 by the exhaust from the conduit 3, this after the passage of the draft below the wall 14 and about or alongside the conduit 3. In passing from the space below the wall 14 to the chamber 1, the draft and the products of combustion are carried in violent contact with the baffle members 17 and 18, and incident to said contact all of the heavy ashes, cinders and flaming particles are deflected through the openings between the baffle members 17 and 18 into the vacuum chamber 21 where they gravitate to the trough 19 so as to be conveyed by the conveyor 22 to a point exterior to the locomotive or boiler casing. The course of the products of combustion is generally circular, and centrifugal action, therefore, causes the ashes and heavy materials to pass between the baffle members 17 and 18. It will also be noticed in this connection that the vacuum chamber 21 contributes to the draft capacity of the locomotive.

The practical advantage of my improvement with parts relatively arranged as stated will be better appreciated when it is stated that the upper flues in a locomotive boiler expel only the lighter ash, the heavier cinders being discharged from the lowermost flues of the locomotive boiler. Thus the baffle members 8 may be depended upon to handle most of the lighter materials, while the baffle members 17 and 18 will deflect the heavy materials and practically all of the light materials remaining in the products of combustion, so that the discharge through the uptake 2 will be practically clear or free of sparks.

It will be apparent from the foregoing that notwithstanding my improvement effectively prevents the emission of sparks from the stack 2, the improvement functions without

any material or serious impairment of the draft necessary to support combustion in the locomotive.

It will also be appreciated from the foregoing that my improvements are simple and inexpensive in construction, and are susceptible of being inexpensively installed.

I have entered into a detailed description of the construction and relative arrangement of the elements comprising in the present and preferred embodiment of my invention in order to impart a full, clear and exact understanding of the said embodiment. I do not desire, however, to be understood as limiting myself to the construction and arrangement as illustrated and specifically described, my invention being defined by my appended claims within the scope of which modifications in structure and in arrangement may be made without departure.

Having described my invention, what I claim and desire to secure by Letters Patent, is:—

1. In a spark arrester, a baffle including members of hollow character tapered from their heel edges to their opposite edges, said baffle and members being curvilinear, and said members being spaced apart with the heel edge of one opposed to the opposite edge of the other.

2. In combination with a locomotive smoke box, a smoke stack, a chamber in communication therewith, a baffle plate defining the rear wall of said chamber, a wall defining the bottom of said chamber, a conduit for exhaust steam extending through said bottom wall, a set of baffle members spaced apart one above the other and arranged in rear of said baffle plate and separated therefrom by an intervening space, conducting means for products of combustion in rear of said baffle members, said conducting means in communication with the space below the bottom wall of the chamber, a curvilinear wall at the forward portion of the bottom wall of the chamber and forming a part of the front of the chamber and also defining the rear wall of an arcuate passage connecting the space below the bottom wall of the chamber and the forward portion of said chamber, and an arcuate set of spaced baffle members defining the forward wall of said arcuate passage.

3. In combination with a locomotive smoke box, a smoke stack, a chamber in communication therewith, a baffle plate defining the rear wall of said chamber, a wall defining the bottom of said chamber, a conduit for exhaust steam extending through said bottom wall, a set of baffle members spaced apart one above the other and arranged in rear of said baffle plate and separated therefrom by an intervening space, conducting means for products of combustion in rear of said baffle members, said conducting means in

communication with the space below the bottom wall of the chamber, a curvilinear wall at the forward portion of the bottom wall of the chamber and forming a part of the front of the chamber and also defining the rear wall of an arcuate passage connecting the space below the bottom wall of the chamber and the forward portion of said chamber, and an arcuate set of spaced baffle members defining the forward wall of said arcuate pas-

sage; in combination with a conveyor trough at the bottom of the space between the baffle plate and the first named baffle members, a conveyor in said trough, a wall in front of the lowermost of the arcuate set of spaced baffle members, a conveyor trough below the space between said baffle members and said wall, and a conveyor in said trough. 15

In testimony whereof I affix my signature.

ROBERT E. MARTIN.
